UNITED STATES PATENT OFFICE

ELMER G. KOCH, OF DAYTON, KENTUCKY, ASSIGNOR TO THE WADSWORTH WATCH
CASE COMPANY, OF DAYTON, KENTUCKY, A CORPORATION OF KENTUCKY

COLLAR FASTENER

Application filed October 5, 1932. Serial No. 636,374.

This invention relates to wearing accessories and is particularly directed to soft collar fasteners of the type adaptable to the collar ends relative to the necktie. The structure of this device is designed as an improvement over the existing type of clasp or fastener now in current use, its general purpose and use being the same, namely to draw the ends of the collar together and to hold them against displacement for maintaining a neat appearance of the collar relative to the necktie.

It is the object of this invention to provide a collar fastener or holder for the described use which is extremely efficient in that it is readily placed in position and does not slip or become detached easily, which is readily applied by the wearer without undue effort and difficulty, and which is fabricated in an improved manner, whereby the assembly operations are relatively simple and no extraneous fastening means are needed in the fabrication.

Other objects and further advantages will be more fully apparent from a description of the accompanying drawing, in which:

Figure 1 is a perspective view of the improved collar fastener, showing it in position of use.

Figure 2 is a front view of the improved fastening device.

Figure 3 is a sectional view taken on line 3—3, Figure 2, detailing the fabricated structure of the fastener.

The present structure is designed to include the least number of parts necessary to the fabrication of an efficient collar clasp or holder and these parts are so arranged as to co-operate in assembly for sturdiness and efficient clasping action. Generally speaking the article is formed of two pieces which are interfixed for providing a pair of spring urged jaws, between which jaws the collar tips or ends are readily engaged, the jaws tending to grip the material of the collar without damage thereto and in such fashion as to be incapable of accidental displacement.

Referring to the drawing, the front plate or bar of the clasp is indicated at 5 and the co-operating clasping or jaw forming element at

6. The front plate or bar providing the ornamental effect for the clasp is curved to approximately the curvature of the average collar at the throat portion thereof. The clasping or jaw forming element 6 is fastened to the front bar at an intermediate point thereof. For this purpose the bar is longitudinally slotted except for end connecting portions 7 and an intermediate connecting portion 8. The clasping or jaw forming element is of a thickness less than the width of the slots and is mounted through the slots as shown in Figure 3.

A loop 9 is formed at the intermediate portion of the element 6 and engages upon and about the intermediate connecting portion 8 of the front bar. When this element 6 is in position, the major portion thereof is disposed along the back of the bar 5. At each end of the jaw forming element substantial barbs are formed providing points 10 for these ends and curved cam surfaces 11 terminating in shoulders 12 or gripping points adapted to engage the material of the collar and press and wedge the same into the slots.

The initial shape of the jaw forming element 6 at the intermediate loop portion prior to assembly is such that the open back of the loop is of a width permitting insertion of this element through the slots and over the intermediate portion. After the element has been inserted, the sides of the loop are drawn together or crimped in back of the connecting portion 8 as at 12. This narrows the opening at the back of the loop and prevents displacement of this element from the rigidly fixed position about the intermediate portion of the bar 5. At this time, the collar contact tips or shoulders at the ends of the element 6 are disposed within the slots, where-as the curved surfaces 11 extend clear of the slots. As will be apparent from Figure 3, it is thereby extremely convenient for the clasp to be inserted upon the collar ends since the edge of the collar is forced between the shoulder or engaging point 12 and the back of the bar by forcing the collar end into the convergence of the curved surface 11 and the rear surface of the front bar. The points 12 are sufficiently pointed to insure, without

damage, a tight grip on the material and the spring action of the element 6 acts to wedge the material of the collar in the slots.

Having described my invention, I claim:

6. 1. A collar fastener, comprising, a front bar including longitudinal slots and an intermediate connecting portion, and a jaw forming element having a longitudinal loop portion secured by crimping about the intermediate portion and having jaw ends disposed adjacent the slots of the front bar with engaging tips disposed within the slots.
10. 2. In a collar clasp, a front bar having longitudinal slots therein and including an intermediate connecting portion, a jaw forming element disposed through the slots and having an intermediate loop pressed about the intermediate portion of the forward bar, said jaw forming element having clamping ends disposed at the rear of the bar and including points disposed within the slots for forcing the material of the collar into the slots and wedging the same in position.
15. 3. In a collar clasp, a front bar having longitudinal slots therein and including an intermediate connecting portion, a jaw forming element disposed through the slots and having an intermediate loop crimped about the intermediate portion of the front bar, said jaw forming element having clamping ends disposed at the rear of the bar.
20. 4. In a collar clasp, a front bar having longitudinal slots toward each end thereof, a jaw forming element disposed through the slots and having an intermediate loop clinched about the intermediate portion of the forward bar, said jaw forming element having clamping ends disposed at the rear of the bar and including points disposed within the slots for forcing the material of the collar into the slots and wedging the same in position, and the ends of the jaw forming element being curved to said wedging points for the purpose of entry.
25. 5. A collar fastener, comprising, a front bar including slots at its ends, a jaw forming element having a longitudinal loop portion secured to said forward bar and having its ends disposed adjacent the back of the front bar with engaging edges disposed for pressing the collar material into the slots.

In witness whereof, I hereunto subscribe my name.

ELMER G. KOCH.
